UNITED STATES PATENT OFFICE.

CHARLES E. NUTTING, OF HOPEDALE, MASSACHUSETTS, ASSIGNOR TO DRAPER CORPORATION, OF HOPEDALE, MASSACHUSETTS, A CORPORATION OF MAINE.

WEFT-FEELER FOR LOOMS.

1,272,702.

Specification of Letters Patent. Patented July 16, 1918.

Application filed November 8, 1917. Serial No. 200,950.

To all whom it may concern:

Be it known that I, CHARLES E. NUTTING, of Hopedale, in the county of Worcester and State of Massachusetts, have invented certain new and useful Improvements in Weft-Feelers for Looms, of which the following is a specification.

The improvements are illustrated in the accompanying drawings, wherein—

10 Figure 1, is a plan view of a shuttle box, partly in section, and of the weft feeler mechanism at the detecting side of the loom. Fig. 2, is a vertical section in the plane indicated by the line 2—2 in Fig. 1. Figs. 3 and 4 are enlarged sectional views of parts illustrated in Fig. 2, illustrating different positions occupied by the weft feeler at different periods in the operation of the loom.

15 In the drawings A, is a portion of the lay at the detecting side of the loom; B, is the shuttle; C, is the weft carrier held within the shuttle by means of elastic spring pressed jaws D; and E, is the front wall of the shuttle box. The front wall of the shuttle box 20 and the front wall of the shuttle are apertured for the reception of the feeler fingers as illustrated in Fig. 1. There are two feeler fingers F, and a. The feeler finger F, is mounted to slide back and forth on a fixed part of the loom in front of the lay. It is 25 moved to the rear by the spring H, and it is moved forwardly in opposition to the spring H, during the forward swing of the lay after the mass of weft I, on the bobbin C, comes 30 in contact with it.

35 The parts thus far described, excepting the feeler finger a, are or may be the same as the correspondingly lettered parts in the weft feeler set forth in United States Letters Patent of Nutting, No. 1,224,775, May 1, 1917.

40 The feeler finger F, is blunt while the feeler finger a, is pointed so as to penetrate the mass I, of weft. The finger a, is carried by the finger F, and is capable of an independent sliding movement on the finger as shown in Figs. 3 and 4. Finger F, is formed with a longitudinal bore b, in which the pointed finger fits and slides. Forward 45 of the bore b, the blunt finger F, has a lengthwise extending slot 3, into which the forward end of the finger a, extends. At its front end the finger a, is provided with an upwardly and forwardly projecting bunter 50 c, which co-operates with the actuator 11.

The actuator is pivoted at 15, to the finger F, in the slot 3. The actuator 11, carries an adjustable abutment 17, which screws into the actuator for adjustment and is held in its adjusted position by means of a lock nut 18. The abutment 17, has a hemi-spherical socket e, in its rear end into which extends the hemi-spherical ball d, of the pointed penetrating finger a. The front notched end 12, of the actuator 11, is maintained in its normally idle uplifted position by means of a spring 20. This spring bears against a collar 21, on a vertically sliding guide pin 19, upon whose upper end the forward end of the actuator 11, normally rests. The upward movement of the pin 19, under the influence of the spring 20, is limited in its movement by the collar 21, abutting against the under surface of a fixed portion of the loom as shown in Fig. 2. Accordingly, the actuator 11, during the normal running of the loom is maintained in its normally uplifted position and slides idly back and forth upon the top of the pin 19, during the reciprocation of the feeler finger F. The abutment 17, is so adjusted that during this normal action the front end d, of the bunter of finger a, is in contact with the abutment 17, as shown in Fig. 2. During this normal action the front end of the actuator 11, rides clear above the controller O, which is pivoted at P, to a fixed part of the loom. This controller O, is similar in its action to the corresponding part of the weft feeler set forth in United States Letters Patent of 50 Northrop, No. 911,672, February 9, 1909. As therein set forth when this controller O is swung forwardly it sets into action the initial portion of the train of mechanism which brings about the weft replenishment. 55

As long as there is an ample supply of weft in the shuttle the pointed finger a, penetrates the mass of weft and the body of the weft encounters the blunt finger F, and moves the forwardly extending finger 60 against the tension of its spring H, without any independent movement being applied to the pointed finger. Hence the actuator 11, moves forwardly with the finger F, without swinging thereon. The spring 20, 65 has sufficient force to enable the pointed finger to penetrate the soft mass of weft without any movement being given to it independently of the blunt finger.

When, however, the supply of weft has 70

been so far depleted that the pointed finger no longer finds sufficient weft in its path to sink into so that it either actually or substantially meets the greater resistance of the 5 bobbin C, (as shown in Fig. 4) the tension of the spring 20, is then overcome and the finger a, moves forwardly within the bore b, of the blunt finger F, and independently thereof. Consequently, the forward movement 10 of the finger a, with respect to the finger F, swings the actuator 11, downwardly as shown in Fig. 4, the spring 20, being compressed and the actuator supporting pin 19, moving downwardly. This action takes 15 place at a period in the forward movement of the lay when the front notched end 12, of the actuator is back of the controller O, when occupying the position shown in Fig. 2. The downward movement of the actuator 20 brings its notched end down far enough so that as the actuator moves forwardly it encounters the controller O. Then, as the lay swings to front center, the actuator 11, carries with it the controller O, to the forward position illustrated in Fig. 4. The 25 controller O, thus swings forwardly on its pivot P, and starts the weft replenishing train of mechanism into action in the manner set forth in the aforesaid Northrop Patent No. 911,672.

It will be noted on referring to the aforesaid Patent No. 1,224,775, that the parts herein referred to by capital letters are similar to the corresponding elements of said 30 patent; whereas, the parts hereinbefore identified by reference numerals are not in said patent but are similar to the like features set forth in United States Letters Patent of Sontag, No. 968,708, August 30, 1910. The present improvements, therefore, reside 35 in the sliding penetrating finger a, capable of back and forth movement independently of the blunt finger F, and relatively thereto, and in the vertical swinging actuator carried by the finger F, and coöperating with 40 the bunter of the pointed finger through the adjustable abutment having a socket into which the rounded end of the bunter enters.

This ball and socket connection between the bunter of the pointed finger and the abutment of the actuator enables the actuator to swing with minimum friction while the pointed finger and its bunter slide and a noiseless contact can be maintained at all times between the bunter and the abutment. 50

I claim—

1. A weft feeler for automatic weft replenishing looms having, in combination, a sliding spring actuated blunt feeler finger; 60 an actuator pivoted upon said blunt feeler finger, said actuator having an adjustable abutment with a socket on its rear end; a spring normally maintaining said actuator in its idle position; and a pointed penetrating finger mounted to slide on said blunt finger, said pointed finger having an upwardly and forwardly extending bunter with a ball on its forward end entering and contacting with the socket on the actuator 70 abutment.

2. A weft feeler for automatic weft replenishing looms having, in combination, a sliding spring actuated blunt feeler finger; 75 an actuator pivoted upon said blunt feeler finger, said actuator having an abutment with a socket on its rear end; a spring normally maintaining said actuator in its idle position; and a pointed penetrating finger mounted to slide on said blunt finger, said 80 pointed finger having a bunter with a ball on its forward end entering and contacting with the socket on the actuator abutment.

3. A weft feeler for automatic weft replenishing looms having, in combination, a 85 sliding spring actuated feeler finger; an actuator pivoted upon said feeler finger, said actuator having an abutment with a socket on its rear end; and a second finger mounted to slide on said spring actuated 90 finger having a bunter with a ball on its forward end entering and contacting with the socket on the actuator abutment.

In witness whereof I have hereunto signed my name.

CHARLES E. NUTTING.
